Telephone Manufacturing Company Limited,
London, England, a British company

Application November 13, 1950, Serial No. 195,437
In Great Britain October 13, 1949

9 Claims. (Cl. 340—373)

1

The present invention relates to indicating mechanisms, and more particularly relates to electrically operated indicators of the kind adapted to give at least a visual indication.

Such indicators are commonly used for example, as calling indicators in manually operated telephone exchanges. In conventional form these calling indicators consist of an electromagnet co-operating with a pivoted armature which is spring loaded to keep it remote from the electromagnet pole piece when the electromagnet is not energised, and an indicating flag or shutter mechanically linked to the armature to give a visual indication when the armature is attracted to the pole piece.

One object of the present invention is to provide a novel construction of indicator which may be more simple than the above mentioned conventional form.

According to the present invention there is provided an indicator of the kind specified comprising an electromagnet having a pair of pole pieces, and a permanently magnetised member arranged for rotation between said pair of pole pieces without contact therewith, the arrangement being such that energisation of said electromagnet causes said member to rotate through a predetermined angle and thereby provide the required indication.

The arrangement may be such that the member is self-restoring to a non-indicating position when the electromagnet is de-energised, or it may be restored manually or by reversing the current through the electromagnet winding.

One embodiment of the present invention will now be described, by way of example, as applied to an indicator adapted for use as a telephone calling indicator, the embodiment being described with reference to the accompanying drawings, in which:

Figure 1 is a plan view of the indicator with part of the electromagnet sheath shown broken away.

Figure 2 is a side view of the indicator in the non-operative condition with one side bracket which supports the cylindrical magnet removed for clarity, whilst

Figure 3 is a part view similar to Figure 2 showing the cylindrical magnet in its operative position, and

Figure 4 is an end view of the front of the indicator.

Referring now to the drawings, it will be seen that in this embodiment the indicator comprises a soft iron sheath 10 of square cross section, open at each end, in which is housed a soft iron core 11 provided with an energising winding 12. A soft iron piece 13 is provided at one end of the sheath 10 to complete a magnetic path between the core 11 and the sheath 10. Joined to the soft iron piece

2

13 is a sheet of insulating material 14 carrying four contact pins 15 to two of which are connected leads from the winding 12. At the other end the core 11 projects through an insulating end plate 16 and has a pole piece 17 in the form of a plate of curved cross section attached thereto. One side of the sheath 10 at this latter end is extended with the first portion of the extended side in the same plane as the remainder of the side, and the other portion bent to form a second pole piece 18 of similar shape to the first pole piece but provided with a rectangular aperture 19 therein. The arrangement is such that the pole pieces 17 and 18 effectively partially enclose a cylinder, with two air gaps between the pole pieces. A circular cylindrical permanent magnet 20 is supported in the space between the pole pieces 17 and 18 by pivots 21 mounted in the side arms of a bracket of non-magnetic material which is secured to the flat portion of the extended side. The mounting of the magnet cylinder 20 and the shape of the pole pieces 17 and 18 is such that the air gap therebetween is not uniform. The air gap between the pole piece 18 and the magnet cylinder 20 decreases from the free end of the pole piece 18 towards the centre whilst the air gap between the pole piece 17 and the magnet cylinder 20 decreases from that end of the pole piece 17 adjacent the extended side of the sheath 10 in a similar manner. At one side of the magnet cylinder 20 a cam member 22 is fitted on the pivot 21 and is adapted to co-operate with stops 23 and 24 to limit the extent of rotation of the magnet 20. The magnet 20 is magnetised transversely to its axis of rotation and is arranged so that with the cam member 22 resting on the back stop 23, the magnetic axis, indicated by the broken line 25 approximately bisects the longitudinal axis of the cam member 22. The cam member 22 co-operates with a pair of off-normal contacts 26 fitted on the insulating plate 16, the contacts 26 being closed by the cam member 22 when the magnet 20 is rotated so that the cam 22 is resting on the front stop 24.

The operation of the indicator is as follows: With the electromagnet winding 12 not energised the location and dimensions of the radial air gaps between the pole pieces 17 and 18 are such that the magnet 20 rests with the cam 22 on the back stop 23. When the electromagnet winding 12 is energised by direct current in the correct direction, however, the resulting magnetic field between the pole pieces 17 and 18 causes the magnet 20 to rotate in order to move the magnet poles nearer to the pole pieces 17 and 18, which brings the cam 22 to rest on the front stop 24.

The shape of the air gaps between the magnet cylinder 20 and the pole pieces 17 and 18 is designed to give a progressively decreasing reluctance and consequently increasing magnetic

attraction at this point, so that the magnet cylinder 20 is accelerated during its movement from the back stop 23. Similarly on the de-energisation the magnet cylinder 20 is accelerated in the course of its restoring movement. When the winding 12 is de-energised the magnet 20 is self restoring to its original position. The magnet 20 is suitably marked, for example with white paint, on the part of the periphery which can be seen through the aperture 19 in the pole piece 18 when the cam 22 rests on the front stop 24, so that this movement of the magnet 20 provides the required indication by virtue of the appearance of the marking in the aperture 19. At the same time the off-normal contacts 26 are made, and these can be used to complete the circuit of any known form of audible indicator for use, for example, as a night alarm.

In use a dust cover of non-ferrous material will be fitted over the pole piece end of the indicator and will overlap the adjacent end of the soft iron sheath. A transparent window will be provided in the end of this cover corresponding to the aperture in the pole piece.

The above described arrangement can be modified slightly where it is desired that the indicator shall not be self restoring. In this modified arrangement the magnet 20 is arranged so that when moving between the back stop 23 and the front stop 24 its magnetic axis passes through the position of maximum reluctance as determined by the shape of the pole pieces. This results in the magnet being in a rest position on either stop so that the indicator remains in the operated position after the electromagnet winding has been de-energised. A simple spring controlled element of conventional type can be used for manual restoration; alternatively the current through the electromagnet winding may be reversed.

Indicators according to the present invention have the advantages over a conventional indicator of the above described form that the magnet which is the usual armature can also function as the indicator, no separate indicating flag with mechanical linkage thereto being necessary. Generally no restoring spring is necessary, although in some modifications a simple element may be used. Thus a simplified construction is possible with resultant ease of assembly and maintenance.

What we claim is:

1. An electrically operated visual indicator comprising an electromagnet having a pair of confronting pole pieces, and a rotatable permanently magnetized member arranged for angular movement between said pair of pole pieces upon energization of said electromagnet, said magnetized member having a part of its periphery distinctively marked whereby a required indication is provided by said magnetized member upon angular movement thereof.

2. An electrically operated visual indicator as recited in claim 1, wherein said pole pieces are of curved cross-section as viewed in a plane transverse to the axis of angular movement of said magnetized member, each pole piece being spaced from the adjacent portion of said magnetized member by an air gap which decreases in radial length from one end of the pole piece circumferentially towards the other end thereof, and the narrow end of each air gap being adjacent the broader end of the other air gap.

3. An electrically operated visual signal indicator as recited in claim 1, in combination with a pair of electrical contacts, and a member se-

cured to said permanently magnetized member and cooperating with said electrical contacts to cause a change of state of operation thereof upon angular movement of said permanently magnetized member.

4. An electrically operated visual indicator comprising an electromagnet having a pair of opposed pole pieces of curved cross section arranged to partially enclose a cylindrical space whilst leaving two air gaps between the pole pieces, a cylindrical permanently magnetised member rotatably supported between said pole pieces for rotation upon energisation of said electromagnet, and stop means limiting the angular rotation of said magnetized member, said magnetized member having a distinctive marking on its periphery, which marking provides the required visual indication upon rotation of said magnetized member.

20 5. An indicator according to claim 4, in which a pair of electrical contacts are provided, and a member secured to said permanently magnetized member cooperates with said electrical contacts to cause a change of state of operation thereof upon rotation of said permanently magnetized member.

30 6. An electrically operated visual indicator comprising an electromagnet, said electromagnet having an energising winding surrounding a central soft iron core and a soft iron sheath enclosing said winding, a pole piece joined to said core and a further pole piece joined to the adjacent end of said sheath, said pole pieces being of curved cross-section and partially enclosing a cylindrical space whilst leaving two air gaps between the pole pieces, and a cylindrical permanently magnetised member rotatably mounted between said pole pieces.

7. An indicator according to claim 6, in which the pole piece joined to the sheath has an aperture therein through which a portion of the periphery of said permanently magnetised member is visible.

45 8. An indicator according to claim 6, in which the air gap between each pole piece and the adjacent portion of said permanently magnetised member decreases from one side of the pole piece to the other.

9. An electrically operated telephone indicator comprising an electromagnet having a pair of arcuate pole pieces, one of said pole pieces having an aperture therein, a cylindrical permanently magnetized rotor, said cylindrical rotor being supported in brackets between said pole pieces, and stop means limiting the movement of said rotor on energisation of said electromagnet, said rotor having a portion of its periphery distinctively marked, said portion being visible through said aperture only in the position of said rotor to which it rotates on energisation of said electromagnet.
